Several factors affect the ability of the brain to store and retrieve information. One of the most important factors is the amount of time spent learning. The more time spent learning, the better the memory retention. Another factor is the type of information being learned. For example, it is easier to remember facts and figures than it is to remember names and faces. The brain also has a limited capacity for storing information, so it is important to use effective study techniques to maximize memory retention.

As a result of the above, the following recommendations are made:

3 Claims.

This invention relates generally to strainer devices.

vices and more particularly to a type of strainer device serviceable in association with the down-spout opening of a gutter on architectural structures, although not limited to such use.

An important object of the present invention is the provision of a new and effective strainer device embodying novel structural features rendering the same easily installed at its place of use.

A further object is the provision of an improved strainer particularly expediently insertable into a narrow space between a roof edge and the lip of an associated eave gutter for attachment about a downspout opening therein.

A still further object is the provision of an improved strainer device possessing the aforesaid novel features, together with structural characteristics that make it extremely inexpensively produced.

Another object of this invention is to provide means for holding the strainer in position at the top of a downspout.

These and other desirable objects encompassed by and inherent in the invention will become apparent from the ensuing description when considered with the single sheet of annexed drawing, wherein:

Fig. 1 is a side view of a strainer device constructed according to the principles of the present invention;

Fig. 2 is a perspective view of the device illustrating an intermediate stage in the installation thereof within the gutter of an architectural structure;

Fig. 3 is a transverse sectional view taken through the gutter illustrated in Fig. 2, but showing the filter device installed within the down-spout opening thereof.

Referring to Fig. 1, my improved strainer device 10 will be seen to have an over-all contour similar to that of an inverted cup. The base portion 11 of the device constituting the brim of the cup-shaped configuration is formed of a metal band bent substantially into a circle. The strainer portion 12 of the device is formed of a plurality of strainer fingers 13 extending axially of the device from an edge of the base portion or band 11, said fingers being narrower at their upper ends where they are bent inwardly, leaving an end opening 14. An opposite end opening 15 is within the base of the device.

A slit 16 is provided in the base portion 11 in circumferential registry with an adjacent pair of the strainer fingers 13 to coact therewith in forming an axial breach traversing the base and

3 Claims. (Cl. 210—170)

strainer portions of the device and communicating between the end openings 14 and 15. This breach in the device enables it to be modified in circumference extent, that is, to be made smaller in circumference when the opposite edges 17 and 18 of that portion of the slit 16 are forced together or to increase the circumferential extent of the device when the breach is widened when the edges 17 and 18 are spread. After bending the various parts of the device into the desired shape, the device will be tempered to render it resilient so that whether the axial breach therein is widened or diminished there will be a tendency to recover to the original shape illustrated in Fig. 1.

My improved device is particularly adapted for installation in a gutter of the character as that shown at 20 in Figs. 2 and 3. Frequently, as shown in Figs. 2 and 3, there is very little space left between the gutter lip 21 and the edge 22 of a roof 23. In such instances there is insufficient room to permit the passage of a conventional strainer device for insertion within a downspout opening as 24 leading into a downspout as 25. Such difficulty, however, is not encountered with the present device, for by spreading the axial breach therein the device can be slipped into coaxial relation with the gutter lip 21, such lip extending through the end openings 14 and 15, and through the hollow interior of the device. After the device is thus associated with the gutter in the manner shown in Fig. 2, it is rotated about the lip 21 to transfer the body of the device into the gutter and thereafter the device is forced into the gutter incident to spreading the axial breach in the device to permit the passage of the lip outwardly therefrom. Following this operation the device is manipulated by means of the workman's fingers extending inwardly through the space between the lip 21 and the roof edge 22. By this manipulation the device is set upright, its base 11 contracted by narrowing the breach at 16, to enable the base to be inserted downwardly into the downspout opening 24. Upon release of the device, its inherent resiliency causes the base to expand, widening the breach but causing the outer periphery thereof to firmly engage the inner periphery of the material about the downspout opening.

50 Since the device is resilient it recovers to the initial or relaxed condition shown in Fig. 1 after spreading of the axial breach in its side wall pursuant to the insertion and withdrawal of the gutter lip 21 incident to installing the device. There-
55 fore the device can be contracted at its base.

for insertion within an opening as the downspout opening 24, or it may be expanded and allowed to contract onto a flange or the like (not shown) for holding it in position over the entrance of a channel from which the device is to exclude debris.

In addition to providing a highly effective device, and one readily installed under adverse conditions, I have also provided a device that is easily and economically constructed. It is conceivable that the device is made from a flat piece of metal stock by a simple stamping operation. Subsequent to preparation of the flat stamping which consists of the strip 11 with the fingers 13 extending perpendicularly from one of its edges, the strip is bent from its straight formation to the generally circular or cylindrical formation shown in Fig. 1 and the free ends of the fingers are bent inwardly by a suitable press, in a manner well known in the art, to impart the desired formation thereto.

In order to keep the strainer from working its way down into the downspout 25, shoulders 26 and 27 are provided near the bases of two of the fingers. As illustrated in Figure 2, these shoulders engage the floor of the gutter 20 and support the strainer in the desired position.

While I have herein shown and described a preferred embodiment with the view of fully illustrating the invention, it should be understood that the invention extends to other forms, arrangements, structures, details and materials falling within the scope and spirit thereof and not sacrificing all of its material advantages.

I claim:

1. A downspout strainer comprising a substantially cylindrical member formed of resilient sheet material, a slit substantially parallel to the axis of the cylindrical member and extending the full length thereof, and a plurality of open ended slots

extending from a first end of the cylindrical member toward the second end to form therebetween a plurality of tines, the spacing between the inside ends of the slots and the uncut or second end of the cylindrical member being such that the cylindrical member can be manually contracted for insertion in a downspout.

2. A downspout strainer comprising a substantially cylindrical member formed of resilient sheet material, a slit substantially parallel to the axis of the cylindrical member and extending the full length thereof, and a plurality of open ended tapered slots extending from a first end of the cylindrical member toward the second end to form therebetween a plurality of tines, the spacing between the inside ends of the slots and the uncut or second end of the cylindrical member being such that the cylindrical member can be manually contracted for insertion in a downspout, and the tips of the tines being bent inwardly toward the axis of the cylindrical member to act as a screen.

3. A downspout strainer comprising a substantially cylindrical member formed of resilient sheet material, a slit substantially parallel to the axis of the cylindrical member and extending the full length thereof, said member being slotted from a first end of the cylindrical member to a point adjacent the second uncut end to form therebetween a plurality of tines, the spacing between the inside ends of the slots and the uncut or second end of the cylindrical member being such that the cylindrical member can be manually contracted for insertion in a downspout, and an outwardly directed shoulder on one of the tines near its base for limiting insertion of the strainer in a downspout.

EDWARD A. ROBERTSON.
